UNITED STATES PATENT OFFICE.

WILLIAM S. HOVEY, OF THREE RIVERS, MICHIGAN, ASSIGNOR TO SHEFFIELD CAR COMPANY,
OF THREE RIVERS, MICHIGAN.

RAILWAY MOTOR-VELOCIPEDE.

No. 862,077.

Specification of Letters Patent.

Patented July 30, 1907.

Application filed February 28, 1907. Serial No. 359,796.

To all whom it may concern:

Be it known that I, WILLIAM S. HOVEY, a citizen of the United States, residing at the village of Three Rivers, county of St. Joseph, State of Michigan, have invented certain new and useful Improvements in Railway Motor-Velocipedes, of which the following is a specification.

This invention relates to improvements in railway motor velocipedes.

10 It relates particularly to that class of railway motor velocipedes illustrated in my co-pending application for Letters Patent for railway motor velocipedes, and is a modification, and, in some respects, an improvement upon the structure there illustrated.

15 The main objects of this invention are, first, to provide an improved railway motor velocipede which is simple and economical in structure and easy and convenient to operate. Second, to provide an improved railway motor velocipede in which the engine, which 20 is of the explosion type, may be readily started. Third, to provide an improved railway motor velocipede which may be operated either by hand, foot, or motor power, as desired.

25 Further objects, and objects relating to details of construction, will definitely appear from the detailed description to follow.

I accomplish the objects of my invention by the devices and means described in the following specification.

30 The invention is clearly defined and pointed out in the claims.

A structure embodying the features of my invention is clearly illustrated in the accompanying drawing, forming a part of this specification, in which,

35 Figure 1 is a detail side elevation of a structure embodying the features of my invention. Fig. 2 is an enlarged vertical section, taken on a line corresponding to line 2—2 of Fig. 1, the engine being shown in full lines. Fig. 3 is a detail section taken on a line corresponding to line 3—3 of Fig. 2. Fig. 4 is an enlarged detail section of a modification in which a gear drive is substituted for the friction drive shown in Figs. 1 and 2. Fig. 5 is a detail section taken on a line corresponding to line 5—5 of Fig. 4. Fig. 6 is a detail plan of the 45 clutch lever. Fig. 7 is a detail vertical section showing shifting or adjustable gear for the driving connections to the hand lever.

In the drawing, the sectional views are taken looking in the direction of the little arrows at the ends of the 50 section lines, and similar numerals of reference refer to similar parts throughout the several views.

Referring to the drawing, the frame preferably consists of the bottom and top longitudinal side rails 1 and 2 which are connected by suitable vertical and trans-

versely-arranged cross pieces. A pair of traction wheels 5. 4 is arranged between the side rails, the same being mounted on suitable axles 3, arranged in bearings 3' carried by the bottom rails 1.

A hand lever 25 is pivoted at 26 and is connected by the pitman 27 to the crank shaft 28. This crank shaft 60 is connected by the train of gears 29 and 30 to the axle of the rear traction wheel. This train of gears is adapted to be disconnected, the gear 30 being adjustable; see Fig. 7. The upper portion of the hand lever is preferably made detachable, it being provided with a coupling socket 31, so that the upper part of the hand lever may be removed, if desired, when the velocipede is being driven by the motor or when it is operated by the feet.

The foot rests 32 are suspended by the pivoted links 70 33 and are connected by the links 34 to the pitman 27, so that the feet may be used to aid in propelling the car, or may be used to propel the same independently of the hand lever. The links 34 are detachable and may be hooked up over the pins 35, when desired, thus holding 75 the foot rests firmly in position.

The engine is mounted at the forward end of the car by brackets 15 and 15' projecting from the frame. The crank shaft 7 of the engine is connected to the shaft 9 by the universal joint 8. On the shaft 9 is a friction wheel 80 10 adapted to engage the friction ring 5 mounted on the inside of the traction wheel. The shaft 9 is eccentrically mounted in the bearing 11 which is adjustable in the bearing block 12, so that the friction wheel 10 may be thrown into or out of engagement with the friction 85 surface of the driving wheel by rotating the bearing in its support. A lever 13 is provided for adjusting this bearing, a suitable segment 14, for retaining it in its adjusted position, being mounted on the top rail of the frame. By thus arranging the parts, the engine may be 90 operated either by hand lever, by the foot rests or by the motor, as desired, and changed from one to the other. I preferably start the car by means of the hand lever or foot rests, after the same is started throwing the friction wheel 10 into engagement, which, of course, 95 will crank up the engine. The engine might, of course, be started by pushing the car after the friction wheel has been thrown into engagement.

The friction ring 5 is preferably made detachable, which permits the application of the engine to structures not specially designed for it. It may be applied to many structures now in general use.

In Figs. 4, 5 and 6, I show modified constructions in which a gear drive is substituted for the friction drive. In this arrangement, the gear 17 is mounted on the 105 crank shaft and the gear 18, arranged to mesh therewith, is mounted on the axle. The hub of the wheel and the gear 18 are provided with clutch members, so that they

may be connected or disconnected at will; the gear 18 being arranged to be shifted on the axle. I preferably accomplish this by means of the rod 20 supported in suitable bearings 21 having laterally-projecting forks at 5 its lower ends, adapted to engage the grooved hubs 18' of the gear. On the upper end of the rod is a hand lever 22. This hand lever is adapted to be engaged on the spring catch 23 for locking the gear into or out of engagement with the driving wheel.

10 I have illustrated in the accompanying drawing, the engine in conventional form, omitting the piping and wiring, as this forms no part of my present invention.

I have illustrated and described my improved velocipede in detail in the form preferred by me, but I am 15 aware that it is capable of considerable variation in structural details without departing from my invention.

Having thus described my invention, what I claim as new and desire to secure by Letters Patent is:

1. In a structure of the class described, the combination 20 with the frame, of traction wheels; a hand lever; pivotally-supported foot rests; driving connections for said hand lever and foot rests to one of said wheels; means for disconnecting said driving connections; an engine; a shaft connected to the engine shaft by a universal joint; 25 a friction wheel on said shaft; a friction ring on one of said traction wheels adapted to be engaged by said friction wheel on said shaft; and an eccentric bearing for said shaft whereby it may be adjusted to bring said friction wheel into engagement with said friction ring, for the 30 purpose specified.

2. In a structure of the class described, the combination with the frame, of traction wheels; a hand lever; driving connections for said hand lever to one of said wheels; means for disconnecting said driving connections; an engine; a shaft connected to the engine shaft by a universal joint; 35 a friction wheel on said shaft; a friction ring on one of said traction wheels adapted to be engaged by said friction wheel on said shaft; and an eccentric bearing for said shaft whereby it may be adjusted to bring said friction wheel into engagement with said friction ring, for the purpose specified.

3. In a structure of the class described, the combination with the frame, of traction wheels; pivotally-supported foot rests; driving connections for said foot rests to one 45 of said wheels; means for disconnecting said driving connections; an engine; a shaft connected to the engine shaft by a universal joint; a friction wheel on said shaft; a friction ring on one of said traction wheels adapted to be engaged by said friction wheel on said shaft; and an eccentric bearing for 50 said shaft whereby it may be adjusted to bring said friction wheel into engagement with said friction ring, for the purpose specified.

4. In a structure of the class described, the combination with the frame, of traction wheels; an engine; a shaft 55 connected to the engine shaft by a universal joint; a friction wheel on said shaft; a friction ring on the rim of one of said traction wheels adapted to be engaged by said friction wheel on said shaft; and an eccentric bearing for said shaft whereby it may be adjusted to throw said friction 60 wheel into or out of engagement with said friction ring, for the purpose specified.

5. In a structure of the class described, the combination with the frame, of traction wheels; a hand lever; pivotally-supported foot rests; driving connections for said 65 hand lever and foot rests to one of said wheels; means for disconnecting said driving connections; an engine; a shaft connected to the engine shaft by a universal joint; a friction wheel on said shaft; and a friction ring on one of said traction wheels adapted to be engaged by said friction 70 wheel on said shaft; and means for adjusting said shaft

to bring said friction wheel into engagement with said friction ring, for the purpose specified.

6. In a structure of the class described, the combination with the frame, of traction wheels; a hand lever; driving connections for said hand lever to one of said wheels; means for disconnecting said driving connections; an engine; a shaft connected to the engine shaft by a universal joint; a friction wheel on said shaft; a friction ring on one of said traction wheels adapted to be engaged by said friction wheel on said shaft; and means for adjusting said shaft to bring said friction wheel into engagement with said friction ring, for the purpose specified. 75 80

7. In a structure of the class described, the combination with the frame, of traction wheels; pivotally-supported foot rests; driving connections for said foot rests to one of said wheels; means for disconnecting said driving connections; an engine; a shaft connected to the engine shaft by a universal joint; a friction wheel on said shaft; a friction ring on one of said traction wheels adapted to be engaged by said friction wheel on said shaft; and means for adjusting said shaft to bring said friction wheel into engagement with said friction ring, for the purpose specified. 85 90

8. In a structure of the class described, the combination with the frame, of traction wheels; an engine; a shaft connected to the engine shaft by a universal joint; a friction wheel on said shaft; a friction ring on the rim of one of said traction wheels adapted to be engaged by said friction wheel on said shaft; and means for adjusting said shaft to throw said friction wheel into or out of engagement with said friction ring, for the purpose specified. 100

9. In a structure of the class described, the combination with the frame, of traction wheels arranged within said frame; a hand lever; pivotally-supported foot rests; driving connections for said hand lever and foot rests to one of said wheels; means for disconnecting said driving connections; an engine mounted on suitable brackets on the outside of said frame; driving connections therefor to one of said traction wheels; and means for disconnecting said driving connections, for the purpose specified. 105

10. In a structure of the class described, the combination with the frame, of traction wheels arranged within said frame; a hand lever; driving connections for said hand lever to one of said wheels; means for disconnecting said driving connections; an engine mounted on suitable brackets on the outside of said frame; driving connections therefor to one of said traction wheels; and means for disconnecting said driving connections, for the purpose specified. 115

11. In a structure of the class described, the combination with the frame, of traction wheels arranged within said frame; pivotally-supported foot rests; driving connections for said foot rests to one of said wheels; means for disconnecting said driving connections; an engine mounted on suitable brackets on the outside of said frame; driving connections therefor to one of said traction wheels; and means for disconnecting said driving connections, for the purpose specified. 120 125

12. In a structure of the class described, the combination of a frame comprising side rails connected by cross pieces; a pair of traction wheels arranged between the side rails of said frame at the front and rear ends thereof; an engine mounted on suitable laterally-projecting brackets on the outside of the said frame, said brackets being located opposite one of said traction wheels; driving connections therefor to said traction wheels; and means for disconnecting said driving connections. 130 135

In witness whereof, I have hereunto set my hand and seal in the presence of two witnesses.
